UNITED STATES PATENT OFFICE.

JAMES N. PAYNE, OF MONTGOMERY, ALABAMA.

DESIGN FOR A COLLAR.

SPECIFICATION forming part of Design No. 35,227, dated October 22, 1901.

Application filed September 22, 1900. Serial No. 30,860. Term of patent 3½ years.

To all whom it may concern:

Be it known that I, JAMES N. PAYNE, a citizen of the United States, residing at Montgomery, in the county of Montgomery and State of Alabama, have invented and produced a new and original Design for Collars, of which the following is a specification, reference being had to the accompanying drawing, forming a part thereof.

10. The drawing represents a plan view of the collar, showing my new design.

As shown in the drawing, the leading or material feature of my design consists of a central longitudinal strip-field *a*, at opposite sides of which extend supplementary strip-fields *b*, which are parallel and at right angles to the central longitudinal strip-field *a*, a longitudinal series of star representations *c* being provided within the area of the strip-field *a*.
20. The strip-fields *a* and *b* and the star representations *c* are collectively provided upon the facial area of the collar, the field *a* being centrally and longitudinally arranged with respect to the fields *b* and the latter series

being arranged to occupy the facial area of 25 the collar outside the field *a*, as shown.

In practice the fields *a* and *b* and the star representations *c* are all of diverse contrasting colors—for instance, the central longitudinal strip-field *a* is one color and the parallel series of strip-fields *b* at opposite sides of the field *a* are another color, while the series of star representations *c* are yet another color.

It is apparent that this design is also applicable to cuffs, shirt-fronts, hat-bands, and 35 other similar purposes.

Having described my invention, what I claim as new, and desire to secure by Letters Patent, is—

The design for a collar, as herein shown and 40 described.

In testimony whereof I have signed my name in the presence of the subscribing witnesses.

JAMES N. PAYNE.
